AMBROSE L. BOUGHTALING, OF PHILMONT, NEW YORK, ASSIGNOR TO
GEORGE W. PHILIP, OF SAME PLACE.

Letters Patent No. 78,968, dated June 16, 1868.

IMPROVEMENT IN DRAWING AND TWISTING-HEAD FOR SPINNING.

The Schedule referred to in these Letters Patent and making part of the same.

TO ALL WHOM IT MAY CONCERN:

Be it known that I, AMBROSE L. BOUGHTALING, of Philmont, in the county of Columbia, and State of New York, have invented a new and useful Improvement in Mechanism for Drawing and Twisting Roving in Spinning-Machinery; and I do hereby declare that the following is a full, clear, and exact description thereof, which will enable those skilled in the art to make and use the same, reference being had to the accompanying drawings, forming part of this specification.

In Sheet I—

Figure 1 represents a top view of a spinning-frame having a pair of my improved drawing and twisting-devices attached.

Figure 2 is a vertical section, taken in the line *z z*.

In Sheet II—

Figure 3 is a front end view of my improved drawing and twisting-device detached, of full size.

Figure 4 is a longitudinal central section taken in the line *y y*, fig. 3.

Figure 5 is a section through the journals of the drawing-rollers, taken in the line *z z*, in fig. 3.

Figure 6 is a side view of the box for supporting the drawing-rollers.

Similar letters of reference indicate corresponding parts.

This invention relates to improvements in that part of spinning-machinery for twisting and drawing, stretching, or condensing the roping, roving, or sliver of wool, cotton, or other fibres, for the manufacture of textile fabrics; and these improvements consist in mechanism connected with a revolving tube or hollow shaft, placed in a stationary frame, whereby the operation of drawing the roving is continuous, and independent of spindles, which may be placed also in the same stationary frame to receive the roving, and spin a continuous thread or yarn.

In the head or front end of the revolving tube is placed a pair of drawing-rollers, of equal size, either smooth or fluted, which lie parallel with and press against each other while rotating on their own axes at right angles to the axis of the revolving tube, and independently of it, while at the same time turning with it end over end, thus receiving a compound motion, which at the same moment twists and draws the roving while it is passing through the tube and between the rollers.

Many attempts have been made to construct a condensing-tube or draw-head of this description, for the purpose of taking the place of the jack and mule with its traversing and intermittent motion, but this object has never been accomplished successfully, so far as I am informed, previous to my invention.

The success of this device depends upon controlling, graduating, adjusting, and regulating the operation of the drawing-mechanism in such a manner that the roving shall be drawn and twisted at the same time with such precision as to stretch and condense the roving evenly without any strain upon the weaker parts, causing thereby an equal distribution of the loose fibres, and producing a filament or roving free from twists or irregularities for the purpose of spinning a level thread.

Four distinct kinds or modes of motion are required in the construction, and are essential in the mechanism of this description of drawing-device for its successful operation, to wit:

1. Conjoint motion. The drawing-rollers must revolve with the condensing-tube, receiving thereby an end-over-end motion, in order to twist the roving passing between them.

2. Independent motion. The drawing-rollers must rotate on their own axes, independently of the condensing-tube, and at right angles to its line of motion, in order to draw the roving passing between them.

3. Positive motion. The drawing-rollers must move with positive gear, at comparatively slow speed, in order to prevent slipping by any irregularity in the driving-power or intervening substance between the rollers, while the condensing-tube moves with greater velocity by means of belt and pulley.

4. Relative motion. The drawing-rollers are geared to run at a speed in relation to that of the condensing-tube according to the size of the roving to be drawn, and the amount of twist required in it.

Three distinct conditions in the mechanism of the drawing-device are also required in order to insure successful operation, to wit:

1. Graduated pressure. The drawing-rollers must admit of exact adjustment, in order to exert the required pressure upon the roving, to regulate the size or tenuity to which the filament is drawn.

2. Elastic bearings. The drawing-rollers must have spring-bearings on their journals, for the purpose of yielding to permit the unobstructed passage through them of any small extraneous matter accidentally associated with the fibrous material of the roving.

3. Relative axial position. The drawing-rollers must admit of exact adjustment in their axial relation to the condensing-tube, so that the line of axis of the tube shall intersect the division-line or point of contact of the peripheries of the rollers; or, in other words, that the rollers shall be exactly central in their relative position opposite the front end of the tube, so that the division-line between the rollers shall always be coincident with a diameter of the tube when the device is in motion. This result is effected by means of equal adjustable bearings upon the journals of both rollers, on their opposite sides, by which each roller can be adjusted separately and independently of the other.

This feature of my invention is of the first importance, and I invite especial attention to it, for its distinctive and effective novelty. Without it, all other conditions of success fail; with it, the drawing-mechanism is rendered complete and perfect in its operation. This, in fact, makes it operative and of practical utility as a machine.

An auxiliary condition of success consists in connected adjustable take-up rollers, the velocity of which can be regulated according to the operation of the drawing-rollers as respects their delivery of the roving, so that there shall be no strain on the loose fibres of the filament after it leaves the drawing-rollers, while at the same time it shall be received and passed by the take-up rolls as fast as it is drawn. Unless these conditions are fully complied with in the construction of the movements of the drawing-mechanism, the operation of drawing the roving cannot be perfect nor practically successful.

These conditions are all embodied in the construction and operation of my improved drawing-mechanism, whereby I am enabled to draw a roving, either woollen or cotton, down to a small size from the spool, as usual, or directly from the card, without the intervention of any other drawing or condensing-mechanism, so that the roving can be conveyed directly to the spindle, and spun in a continuous thread of fine perfectly level yarn.

I consider the yarn thus produced by my improved drawing-mechanism is far superior in quality, when made of similar stock, than is produced usually by the jack and mule, which result is practically demonstrated by full-sized spinning-frames provided with my improved draw-heads, and now in actual operation. A great improvement may thus be introduced in textile manufactures.

This improvement in drawing-machinery thus really dispenses with the necessity of employing jacks and mules, and all other condensing and drawing-devices in woollen and cotton-spinning. The enormous cost of the delicate and complicated mechanism of jacks and mules is thereby saved. The device is simple, compact, and durable, and occupies a very small space in a mill compared with the immense room required for the operation of a jack or mule.

As it occupies a stationary position, and draws the roving continuously, the spindle is supplied constantly, and works without intermission until the cop is full, thus enabling a frame of twenty spindles to perform a much greater quantity of work than a jack or mule with many more spindles. This improved drawing-device has the advantage, therefore, of providing for the introduction of great economies and superior quality in the manufacture of textile fabrics.

The drawing represents a spinning-machine with a pair of my improved drawing-devices attached to it, in which A is the frame, B the driving-shaft, C is a drum, belted to the spindles D, and also to the draw-heads, the mechanism of which will be hereafter described.

The driving-shaft B gives motion to the back set of feed-rollers $a a^1 a^2$ through the medium of one train of gear-wheels, and also to the front set of take-up rollers $b b^1 b^2$ by another train of gear-wheels. Behind the feed-rolls is placed the drum E, on which the spool F rests loosely, to supply the feed-rolls with roving in the usual way.

Between the feed-rollers $a a^1 a^2$ and the take-up rollers $b b^1 b^2$ are placed horizontally the condensing-tubes c c, in line with the spindles respectively, which tubes are hung in bearings, d d, that are to be fitted in connection with adjustable side rails, whereby the distance between the tubes and the feed-rollers may be adjusted as required, according to the nature of the roving. The condensing-tubes receive their motion by straps or bands, e e, from the drum C.

On the front end of each tube c is fitted, to turn loosely upon it, a spur-wheel, g, that engages with an intermediate driving-wheel, h, as shown clearly in fig. 2, sheet 1. An adjustable pulley, H, fits against the inside bearing, d, of the tube. On the front side of the spur-wheel g is a skew-bevel or shouldered wheel, i, that engages two bevel-wheels, k k, fitted on the opposite ends of two parallel drawing-rollers, m m, placed at right angles in front of the tube c, and set in a square-formed head or open box, having sides, n n, in which are the bearings of the rollers, and caps or end-pieces, o o, that are screwed upon the sides of their four corners, to give absolute rigidity to the head, as shown in figs. 3, 4, 5, Sheet II.

The journals of the drawing-rollers m m are inserted in recesses p p, in the sides n n, the inner and outer parts of which sides are connected merely by a neck, q, between the rollers, so that the journals shall have no inner bearings, but allow the rollers to be pressed against each other by slide-boxes or follower-bearings, s s, on their outer sides, as shown in fig. 5, Sheet II.

The boxes or bearings, s s, of each roller are connected by a thin bar-spring, r, to be made $\frac{1}{2}$ "x $\frac{1}{4}$ " semi-

These spring-bearings are placed over the journals of the drawing-rollers $m m$, and under the caps $o o$, and they are adjusted and borne down upon the journals to press them together by set-screws, $u u$, in the centre of the caps, as shown in figs. 3, 4, 5. A jam-nut may be put on each screw, on the outside of the cap. Each drawing-roller is thus rendered capable of adjustment to the axial line of the condensing-tube, as previously described, separately and independently of the other.

In the operation of this drawing-device, the roving passes from the feed-rollers $a a^1 a^2$ into the tube c , and through it between the rollers $m m$, which deliver it, when drawn by them, to the take-up rollers $b b^1 b^2$, from which it goes directly to the flier of one of the spindles D , to be spun, or to a spool, to be wound upon it, if desired.

An arrangement can be made with double or treble sets of drawing-devices, placed in one frame, by which the roving may be doubled and drawn still finer at each operation before passing to the spindle.

The operation of drawing the roving is subject to perfect control by the regulation and adjustment of the mechanism previously described.

It will be observed that—

First, the drawing-rollers $m m$, placed in the head of the condensing-tube c , at right angles to its axis, revolve with it, end over end.

Second, that they receive motion on their own axes by means of the bevel-wheels $k k$, from the bevel-wheel i , on the spur-wheel, g , that takes its motion from the driving-wheel h , and, turning loosely upon the tube, gives the drawing-rollers an independent motion on their axes at right angles to the axis of the tube.

The rollers thus receive, by means of their combined, conjoint, and independent motion, a compound motion, by which the roving, when passing between them, is both drawn and twisted simultaneously, the strain extending equally between the drawing and the feed-rollers upon all the fibres, and stretching the filament in every part alike without breaking it at weaker parts, or producing an undue separation of the fibres to make "twists" or irregularities in the roving and unevenness in the yarn, which would result from unequal strain in drawing without simultaneous twisting of the roving.

Third, that the drawing-rollers $m m$, being thus connected with cog-gearing, have a positive motion, whereas the condensing-tube c is driven by a belt. Thus the drawing-rollers cannot slip, to which defect, in operation, they would be liable if driven by a belt.

Fourth, that the speed of the drawing-rollers is adjusted relatively to that of the condensing-tube by a change in the gear-wheels $k k$, or the driving-wheel h , in the usual way, as desired.

It will be observed also that the drawing-rollers $m m$ admit of exact graduation or adjustment of their pressure against each other, by means of the double-acting spring-bearings $s s$ operating in opposite directions upon the journals of both rollers by means of the set-screws $u u$ working through the caps $o o$. The effect of this pressure upon the rollers is to make them bear upon and bite the roving, more or less, as it passes between them, and thus graduate and regulate the draught, so that the roving may be drawn according to the degree of pressure upon it. The harder the pressure of the rollers, the greater the draught and finer the roving will be drawn.

Also, that the springs $t t$, on the bearings, will yield on both drawing-rollers equally, if any extraneous matter should be introduced with the roving between the drawing-rollers, and thus allow it to pass without interfering with their operation and breaking the filament.

Thus the drawing-rollers are automatic in their operation, moving apart equally from the central line of division between them on opposite sides of the axis of the condensing-tube, after they have been adjusted or set, whatever may be the irregularity of the roving passing between them.

For this reason an excellent yarn can be made by my improved drawing-device of the most irregular fibres of wool or cotton, and even of shoddy-stock full of foreign matters and imperfections.

Also, that the independent adjustable bearings on opposite sides of both the drawing-rollers permit an exact adjustment of the rollers centrally in front of the condensing-tube c , so that the axis thereof shall intersect the division-line or point of contact between the two rollers, as shown clearly by the red line in fig. 4, Sheet II, which condition is necessary, as previously stated, in order that they shall receive and maintain the roving in the axial line or centre of the condensing-tube, when in operation, without any wobbling motion to the roving, the effect of which would be irregularity in the draught, and consequent liability to breakage and imperfection of the thread that would render the machine inoperative, and of no practical utility.

The least wear of the journals or rubbing parts of the rollers would produce irregularity in their action, and throw them out of true if they were not provided with the means for the most accurate adjustment of each roller independently of the other. The tightening-screws $u u$ compensate for wear on either roller, as required.

It will be observed also that the take-up rollers $b b^1 b^2$ should not draw on the roving, but only receive it after it has passed through the drawing-rollers. In order to secure this object, and effect perfect accord of movement in the operation between the take-up rollers and the drawing-rollers, the take-up rollers are made capable of adjustment, as to speed, by a change of gears in the usual way, which will adapt their motion to that of the drawing-rollers, and enable them to receive the roving as fast as delivered without any strain upon the loose fibres of the filament.

I am aware that a machine for unmaking rope or cordage, or to effect the separation of the strands of old rope, for the purpose of reducing it to its original fibrous condition, has been previously employed, in which a pair of adjustable drawing or feed-rollers are placed at right angles to the axis of a hollow shaft or tube, and rotated by means of positive gear, which drawing or feed-rollers, as applied to said purpose, are set apart and have annular grooves in them, opposite each other, centrally, the said grooves being provided with short teeth in their bottoms to bite firmly against the point of a stationary mandrel placed in line with the axis of the

hollow shaft, with its pointed end entering or nearly entering between the said rollers for the purpose of opening and unloring the strands by the entry of the mandrel into the centre of the rope, while the rope has a rotary motion.

I therefore disclaim the use of said adjustable drawing or feed-rollers constructed with their sides or peripheries set apart, and having annular grooves in them provided with teeth, as and for the purpose described; and I do expressly confine and limit my claims to adjustable drawing-rollers, constructed with straight parallel sides or peripheries, which bear upon each other to bite upon the roving while it passes between the rollers, when they are in operation, as hereinbefore described, for the exclusive purpose of twisting and drawing the roving, and not for the purpose of unloring or separating the strands of old rope, cordage, or yarn of any kind whatever.

And now, having minutely described the construction, operation, and advantages of my improved machine for twisting and drawing roving, and defined clearly its special application and use,

What I claim especially, and desire to secure by Letters Patent, is—

1. The combination of the independently-adjustable drawing-rollers *m m*, having straight parallel sides, with the twisting-tube *c*, to the axis of which they are always maintained in central relation, as and for the purposes herein described.

2. The combination of the drawing-rollers *m m*, having straight parallel sides and adjustable independently on opposite sides of the axial line of the twisting-tube *c*, with the positive gears *k k* and the tube, substantially as and for the purpose described.

3. The pair of adjustable sliding bearings *s s*, connected by the springs *t t* respectively, and fitted in the opposite recesses *p p*, in the box *n n*, in combination with the drawing-rollers *m m*, having straight parallel sides, all constructed and operating substantially as and for the purposes described.

4. The combination of the adjustable take-up rollers *b b' b'*, or their equivalents, with the adjustable drawing-rollers *m m*, and the twisting-tube *c*, arranged and operating in connection therewith, substantially as and for the purpose specified.

The above specification of my invention signed by me, this 16th day of December, 1867.

AMBROSE L. HOUGHTALING.
